UNITED STATES PATENT OFFICE.

HENRY S. HALE, OF PHILADELPHIA, PENNSYLVANIA.

CAR-SEAT.

SPECIFICATION forming part of Letters Patent No. 691,373, dated January 21, 1902.

Application filed February 23, 1901. Serial No. 48,443. (No model.)

To all whom it may concern:

Be it known that I, HENRY S. HALE, of the city and county of Philadelphia and State of Pennsylvania, have invented an Improvement 5 in Car-Seats, of which the following is a specification.

My invention relates to car-seats; and it consists of certain improvements which are fully set forth in the following specification 10 and shown in the accompanying drawings.

A part of my invention relates to the means for automatically rocking a foot-rest to shift its position when the seat-back is shifted.

It is one of the objects of my invention to 15 provide simple and efficient means for automatically effecting the shifting of the foot-rest in a car-seat in which the seat-back-shifting arms consist of two members independently pivoted at their ends to the seat-frame 20 and seat-back in such a way as to automatically reverse the seat-back in the act of shifting it.

It is also one of the objects of my invention to provide a simple and efficient construction 25 for simultaneously effecting the shifting of the seat-cushion and the rocking of the foot-rest with the shifting and reversal of the seat-back.

In the drawings, Figure 1 is a transverse 30 vertical sectional view of a car-seat embodying my invention, taken on the line xx of Fig. 3. Fig. 2 is a plan view of one of the end frames of the seat-cushion. Fig. 3 is a rear elevation of the car-seat, and Fig. 4 is an enlarged view of part of the shifting and foot-rest-operating mechanism.

a are the usual stationary frames, to which the back shifting and reversing side arms are pivoted. In the construction shown each of 40 these side arms consists of two parallel members b c , pivoted at their lower ends to the frames a u or to a plate or frame n , carried thereby, and at their upper ends to the seat-back or to a plate or frame o , carried thereby.

45 The members b c overlap at one end, so that the upper and lower pivots of each member are located on opposite sides of the central line, and when the seat-back is shifted it is automatically turned or rotated on the upper 50 pivots of the side arms. This construction is well known.

d are the frames which carry the seat-

cushion and are supported and guided on the usual supports e e .

f is a foot-rest forming part of a rocking 55 foot-rest structure suitably supported below the seat-cushion. As shown, the foot-rest structure consists of arms g g , carried by a rock-shaft h , journaled in the side frames a a , and the foot-rest bar f , carried by the arms 60 g g . Power is transmitted from one of the members of the side arms to the foot-rest structure, so that the foot-rest will be rocked from one side to the other when the side arms are shifted. As shown in the drawings, the 65 lower end of each side arm c carries a toothed segment i , which engages a toothed segment k , carried by the rock-shaft h , the arrangement of the segments being such that the outer teeth are in engagement when the foot-rest is thrown to the rear and the side arms 70 are in either extreme position, as shown in Fig. 1. As the side arms are rocked on their pivots the segments i will move the segments k and rock the foot-rest f to the other side of 75 the seat, which by the shifting of the seat-back becomes the rear. The foot-rest is thus always at the rear of the seat, and the front portion of the seat is open to afford space for storing baggage.

For the purpose of shifting the seat-cushion frames d d when the seat-back is shifted I employ an extension j on each arm b , engaging the adjacent side frame, so that when the arms b are rocked on their pivots the 85 frames d d will be shifted in their guides e e . As shown, the extension j is provided with a lug or pin l , engaging a recess m in the frame d .

The details of construction may be varied without departing from the invention.

What I claim as new, and desire to secure by Letters Patent, is as follows:

1. In a car-seat the combination of rocking side arms pivoted at their lower ends, toothed segments carried by the lower ends of said side arms, a rocking foot-rest structure, and toothed segments carried by said foot-rest structure and directly engaging the toothed segments of the side arms, whereby the rocking of the side arms on their pivots will effect 95 the rocking of the foot-rest structure.

2. In a car-seat, the combination of rocking side arms each consisting of two members independently pivoted at their lower ends, a

seat-back pivoted to the upper ends of said members, a toothed segment carried by the lower end of one of the members of each side arm, a rocking foot-rest structure, and toothed segments carried by said foot-rest structure and directly engaging the toothed segments of the side arm members.

3. In a car-seat, the foot-rest-shifting mechanism consisting of a rocking side arm pivoted at its lower end and carrying a toothed segment *i*, and a rocking foot-rest structure carrying a toothed segment *k* directly engaging said segment *i*.

4. In a car-seat, the foot-rest-shifting mechanism consisting of a rocking side arm pivoted at the lower end and carrying a toothed segment *i*, a rock-shaft, a toothed segment *k* carried by the rock-shaft and directly engaging said segment *i*, and a foot-rest carried by said rock-shaft.

5. In a car-seat, the combination of seat-cushion frames and their guides, the side arms each consisting of two members pivoted at their lower ends, one of the members of each side arm being provided with a toothed segment, a rocking foot - rest structure, toothed segments carried by said rocking foot-rest structure and directly engaging the toothed segments on the members of the side arms, a connection between the other member of each side arm and the seat-cushion

frames, and a seat-back pivoted to the upper ends of the members of the side arms, whereby the seat-cushion frames are shifted and the foot - rest structure is rocked simultaneously with the shifting and reversal of the seat-back.

6. In a car-seat, the combination of seat-cushion frames, guides upon which said seat-cushion frames are supported and guided in their movements, a rocking foot-rest structure, rocking side arms, each consisting of two members independently pivoted at their lower ends, a seat-back pivoted to the upper ends of the members of said side arms, and power-transmitting connections between one member of each side arm and the seat-cushion frames and between the other member of each side arm and the foot-rest structure, whereby the seat-cushion frames are shifted by one of the members of the side arms and the foot - rest structure is rocked simultaneously therewith by the other member of said side arms with the shifting and reversal of the seat-back.

In testimony of which invention I have hereunto set my hand.

HENRY S. HALE.
